UNITED STATES PATENT OFFICE.

JOHN MALCOLM FERGUSON AND ARTHUR WILSON EVANS, OF SYDNEY, NEW SOUTH WALES, AUSTRALIA.

PREVENTING THEFT OF MOTOR CARS.

Application filed September 22, 1924, Serial No. 739,181, and in Australia June 19, 1924.

This invention relates to motor cars and similar vehicles but more particularly refers to the prevention of their use by unauthorized persons.

5 Various devices have been proposed for rendering the theft of motor cars impossible or extremely difficult but have not been successful as their effect can generally be neutralized in a short time by persons conversant with the mechanism of the car.

Now the object of this invention is to provide a device which will render unauthorized use of the car, if not impossible, an undertaking requiring a considerable amount 15 of ingenuity and time.

A further object is to provide a device for the purpose which during the normal running of the car may be usefully used for admitting extra air to the engine. Further 20 the device will not hinder the free movement of the vehicle by hand.

Accordingly the invention consists in providing an extra air device of such a type that it normally tends to remain fully open 25 and providing means whereby this device may be locked in its open position and also providing means whereby manipulation of the device is rendered particularly difficult.

The device consists of a cylindrical vessel 30 which is arranged to communicate with the induction pipe and which is provided with a plunger and a number of peripheral air inlet holes, the plunger being provided with a spring which normally tends to withdraw 35 it to allow air to pass to the induction pipe.

The plunger is controlled in any well known manner from the instrument board of the car where a device for locking it in the "open" position is provided.

40 Enveloping the inlet vessel is a sleeve provided with ribs or flutes and number of holes and which is rotatably attached to it by means of a cap securely fastened thereto in such a manner as to render its removal 45 difficult and laborious.

The apparatus is used for the supply of extra air in the usual well known manner and when the car is not in use the extra air device is locked so that the induction 50 pipe is in full communication with the atmosphere thus rendering starting impossible and moreover by reason of the loose fixing of the enveloping sleeve and its construction it is exceedingly difficult to prevent the ingress of air.

The spring of the plunger is so arranged that on the severing of the control it automatically raises the plunger to allow air to enter the induction pipe in large quantities and means is provided for positively holding the plunger in that position. 60

In the accompanying drawings:

Figure 1 is a sectional elevation of the device, and

Figure 2 is an extended perspective view 65 showing the construction and arrangement of the parts.

The admission of the air to the induction pipe 4 through the peripheral holes 3 in the cylindrical inlet vessel 5 is controlled 70 by the plunger 6 which is manipulated by means of the wire 7 enclosed in the small tube 8, the vessel 5 being screwed into or otherwise affixed to the induction pipe 4. The vessel 5 is also provided with a cover 75 9 towards which the plunger 6 unless restrained by the wire 7 is pushed by the spring 10 to allow air to pass through the holes 3. The cover 9 is recessed to receive the loosely fitting hood or sleeve 11 which 80 is provided with holes 12 and ribs 13 to give it a rough surface and which is rotatably retained by the cap 14 which is affixed by means of screws 15 to the cover 9, the heads of the screws being protected with a 85 thick coating of solder or the like 16. The cap 14 is provided with a central boss 17 which receives the tube 8 and allows the wire 7 to pass to the plunger 6. The necessary movement is imparted to the wire by 90 any well known device 18 which is situated where convenient, for example, on the instrument board 19 of the car and which is capable of being locked by a key 20 or any other well known device. 95

In operation the device 18 is unlocked so that the plunger 6 may be operated to cut off the air supply in order to allow the engine to be started and the device is used in the usual manner while running. When 100 the car is left unattended the plunger 6 is withdrawn and locked in that position so that it is not possible to start the engine.

Should the pipe 8 be cut the spring 10 would act to open the air holes 3 and because 105 of the loose manner in which the sleeve 11 is fitted the whole device could not be removed without considerable trouble in removing the solder 16, the screws 15 and the cap 14. Moreover it would be difficult 110

to prevent air reaching the holes 3 by reason of the construction of the hood 11 and the irregular spaces left between it and the induction pipe.

- 5 As a further safeguard and to prevent manipulation by means of the free end of the wire a slot 21 is formed near the lower end of the plunger 6 and on the exterior of the cylinder 5 a spring ring 22 having an end 23 inwardly projecting through the hole 24 is provided. If the tube 8 and wire 7 are cut, the plunger 6 is forced upwards by the spring 10 until the end 23 enters the slot 21 whereupon the plunger is secured so that air holes 3 are uncovered. The plunger cannot then be released until the whole device is removed. In normal operation for the purposes of supplying extra air the plunger is never withdrawn sufficiently to enable the spring 23 to enter the slot 21.

The device does not make it absolutely impossible to start the engine, but the time necessary to do so when the device is fitted would in most cases prevent theft.

- 25 In the above description the cap 14 is described fixed in position by screws 15 and an overlying ring of solder. It is obvious that this cap may be secured in any well known manner as, for example, by rivets or other equivalent devices.

We claim:—

1. Apparatus for the purposes specified comprising in combination with the induction pipe of a vehicle engine an extra air device connected with the induction pipe and a loosely fitting perforated sleeve enveloping said device.

2. The combination with the induction pipe of an engine, of an extra air device connected with the induction pipe, means for locking said device and a perforated roughened sleeve enveloping said device.

3. A device for the purposes specified including in combination with the induction pipe of an engine, an extra air device adapted normally to give full opening to the induction pipe, a rotatable perforated sleeve surrounding said device, means for securely retaining said sleeve and means for locking said extra air device.

4. A device for the purposes specified including in combination with the induction pipe of an engine, an extra air apparatus adapted normally to maintain full com-

munication between the induction pipe and the atmosphere, a roughened perforated sleeve surrounding said device, means for securely retaining said sleeve, means for operating and locking said extra air apparatus and means for automatically rendering said apparatus inoperative upon the severance of the connection to the locking means.

5. A device for the purposes specified comprising in combination an extra air device which consists of a cylindrical vessel in communication with the induction pipe and having peripheral holes therein, a plunger adapted to be externally operated and a spring adapted normally to operate said plunger to establish full communication between the atmosphere and the induction pipe, a roughened perforated enveloping sleeve, means for securely retaining said sleeve, means for operating and locking said extra air device and means for automatically rendering said plunger inoperative on the severance of the connection to the locking means.

6. A device as claimed in claim 5, wherein the plunger is provided with a circumferential groove and wherein the casing is provided with a hole and wherein the means for automatically rendering the extra air device inoperative includes a spring ring surrounding the casing, and having an inwardly projecting end passing through said hole and adapted for engagement with the circumferential groove in the plunger.

7. An arrangement of the character described including the combination with the induction manifold of an engine of an extra air device in communication therewith and a protecting sleeve surrounding the device consisting of a cap-like body, the outer surface of the side walls of which are provided with corrugations and with openings, and means for rotatably securing the cap-like body in position.

8. An arrangement as claimed in claim 7, wherein the extra air device includes a cylindrical perforated vessel attached to the induction pipe, and a cap closing the upper end of said vessel and acting to secure the sleeve in position.

In testimony whereof they have affixed their signatures.

JOHN MALCOLM FERGUSON.
ARTHUR WILSON EVANS.
